(57) **CLAIM**

I claim the ornamental design for a shoe dryer insert as shown and described.

DESCRIPTION

FIG. 1 is a rear perspective view of the shoe dryer insert invention;

FIG. 2 is a rear perspective view of a shoe dryer insert with a hidden line boot thereon, and the boot forms no part of the design;

FIG. 3 is a side elevation view thereof;

FIG. 4 is a front elevation view thereof;

FIG. 5 is a rear elevation view thereof;

FIG. 6 is a top view thereof;

FIG. 7 is a bottom view thereof;

FIG. 8 is section view 8—8 from FIG. 6; and,

FIG. 9 is section 9—9 from FIG. 6.

The broken line showing of a shoe is for illustrative purposes only and forms no part of the claimed design.
